UNITED STATES PATENT OFFICE.

JAMES ALLAND, OF BOSTON, MASSACHUSETTS.

DESIGN FOR A BOTTLE.

SPECIFICATION forming part of Design No. 36,493, dated August 11, 1903.

Application filed February 24, 1903. Serial No. 144,926. Term of patent 14 years.

To all whom it may concern:

Be it known that I, JAMES ALLAND, of Boston, in the county of Suffolk and State of Massachusetts, have invented a certain new, original, and ornamental Design for a Bottle, of which the following is a specification, reference being had to the accompanying drawing, forming a part thereof.

The drawing represents a perspective view
10 of a bottle embodying my design.

I claim—

The ornamental design for a bottle, as shown.

In testimony whereof I have affixed my signature in presence of two witnesses.

JAMES ALLAND.
